INVENTOR:

Edward P. Beach,
BY Spaketo ATTY'S.

UNITED STATES PATENT OFFICE.

EDWARD P. BEACH, OF NEWARK, NEW JERSEY.

DESIGN FOR A BRACELET.

SPECIFICATION forming part of Design No. 19,472, dated December 10, 1889.

Application filed October 16, 1889. Serial No. 327,226. Term of patent 3½ years.

To all whom it may concern:

Be it known that I, EDWARD P. BEACH, a citizen of the United States, residing at Newark, in the county of Essex and State of New Jersey, have invented and produced a new and original Design for Bracelets; and I do hereby declare the following to be a full, clear, and exact description of the invention, such as will enable others skilled in the art to 5
10 which it appertains to make and use the same, reference being had to the accompanying drawings, and to letters of reference marked thereon, which form a part of this specification.
15 In said drawings, Figure 1 is an edge view of a bracelet embodying my design. Fig. 2 is a face or plan view of a section or portion thereof.
20 Similar letters of reference indicate like parts in each figure where they occur.

The two views are deemed sufficient to fully illustrate my design, the leading feature of which consists in the peculiar configuration presented by the inner and outer surfaces of

the bracelet. When viewed from the inside 25 or outside, both being the same, the configuration is clearly represented in Fig. 2, in which are shown two wires, which form two regular curvilinear lines *a* and *c*, crossing one another at the center and interlaced 30 throughout with two other wires, forming two spirals *e* and *i*, which lie on either side of and across *a* and *c* alternately.

What I claim is—

The design for a bracelet or necklace herein 35 shown and described, the surface of which shows two curvilinear lines *a* and *c*, crossing one another at the center, and being interlaced throughout with two other spirals *e* *i*, 40 which lie on either side of and cross *a* and *c* alternately, as set forth.

In testimony that I claim the foregoing I have hereunto set my hand this 12th day of October, 1889.

EDWARD P. BEACH.
